CLAIM

The ornamental design for a bracket for shaping curtains or similar articles, substantially as shown and described.

DESCRIPTION

FIG. 1 is a front, right side and top perspective view of a bracket for shaping curtains and similar articles showing my new design;

FIG. 2 is a rear, left side and bottom perspective view thereof;

FIG. 3 is a top plan view thereof;

FIGS. 4 and 5 are respectively rear and front elevational views thereof;

FIG. 6 is a right side elevational view thereof;

FIG. 7 is a bottom plan view thereof; and

FIG. 8 is a side elevational view thereof, with the bracket inverted and viewed from the side opposite that shown in FIG. 6.
